UNITED STATES PATENT OFFICE.

ANDREW J. NEAFIE, OF MOUNTAIN LAKES, NEW JERSEY.

RAIL-JOINT.

1,399,269.

Specification of Letters Patent.

Patented Dec. 6, 1921.

Application filed December 22, 1920. Serial No. 432,472.

To all whom it may concern:

Be it known that I, ANDREW J. NEAFIE, a citizen of the United States, residing at Mountain Lakes, in the county of Morris 5 and State of New Jersey, have invented a certain new and useful Improvement in Rail-Joints, of which the following is a specification.

The invention relates to means for joining and supporting the abutting ends of railway rails, and the main object of the invention is to provide a base-plate on which the joined rail-ends are reliably supported between adjacent ties with freedom of the 15 rail to creep thereon in the direction of travel, and which may be easily and economically shifted to the next advance tie when the rail-joint has advanced by such creep.

Another important object is to provide the base-plate with spike-holes so located as to match the spike-holes in the tie-plate employed, so that in such advance of the base 20 plate the spikes for the forward end of such plate will be received in the holes left vacant in the tie by the removal of the forward tie-plate, and the spikes for the latter will be received in the holes in the rearward tie left vacant by the shifting of the base 25 plate, thus avoiding damage to the ties in making the shift.

Another object is to provide rail-bars for connecting the abutting ends of the rails, so constructed as to join such ends strongly 30 and stiffly without connection to the base-plate, and also to be reversible when worn by the impact thereon of the rail-heads and thus permit the presentation of an unworn surface to such impact without requiring 35 the installation of new bars.

The invention consists in certain novel features and details of construction and arrangement by which the above and other objects are attained, to be hereinafter 40 described and claimed.

The accompanying drawings form a part of this specification and show the invention as it has been carried out in practice.

Figure 1 is a plan view of a rail-joint, 45 showing the base-plate bridging two ties, and a standard tie-plate on the adjacent forward tie. The dotted lines show the positions of the parts when the base-plate has been advanced and the rearward tie- 50 plate secured on the vacated tie.

Fig. 2 is a side elevation corresponding to Fig. 1.

Fig. 3 is an end elevation of the joint, with the rail shown in vertical transverse section.

Fig. 4 is a vertical transverse section through the rail-joint, taken on the line 4-4 in Fig. 2.

Fig. 5 is a plan view of the upper face of the base-plate alone.

Fig. 6 is a corresponding longitudinal vertical section, taken on the line 6-6 in Fig. 5, and partly in elevation.

Fig. 7 is an elevation showing the inner face of a portion of one of the reversible 70 rail-bars.

Referring to the drawings, 1, 2 and 3 indicate the three ties included in the operation of the invention. 4 is a base-plate shown as secured to the central tie 2 and 75 rearward tie 3 and bridging the space between them, and 5 is a tie-plate secured to the forward tie marked 1.

The joint at 6 between the rail-ends 7 and 8 lies on the base plate and the rail-ends are 80 supported by the latter. On the base-plate 4 are longitudinal ribs 9 and 10 forming a shouldered channel in which the base of the rail is received to prevent lateral movement of the rail-ends. The ribs or ridges 9 and 85 10 are formed integrally with the body of the plate and are preferably of sufficient width or lateral thickness to permit reclaiming when worn, to receive rails of greater 90 width of base. Beyond the ribs, on each side of the plate, the upper face is formed with shallow grooves as at 11 and 12 to match approximately the under faces of the heads of standard screw-spikes or other fastening means.

The tie-plate 5 is shown as held by screw-spikes 13, 14 and 15, and performs its usual function.

At the forward end of the base-plate, on the outer side, are spike-holes 16 and 17 and 100 on the inner side, 18 and 19, and at the rearward end on the outer side, 20 and 21, and on the inward side, 22 and 23. Screw-spikes 24 and cut-spikes 24^a in all the holes hold the base-plate securely to the ties 2 and 3. 105 The holes 17, 18, 21 and 22 are in the shallow grooves 11 and 12. The holes 16, 19, 20 and 23 extend through the ribs 9 and 10 and the flanged heads of the cut-spikes therein are thus held above and out of con- 110

tact with the rail-base while overhanging the latter to limit the rising movement of the rail ends, as usual.

When the creep of the rail has moved the joint 6 forward, as indicated in dotted lines in Figs. 1 and 2, the spikes 13, 14 and 15 in the tie-plate 5 are withdrawn and the tie-plate removed. The spikes 24 and 24^a, are also removed from the base-plate 4 and 10 the latter shifted forward to bridge the space between ties 1 and 2, with the spike holes 16, 17 and 19 matching the holes in tie 1 left vacant by the spikes 13, 14 and 15 of the removed tie-plate, and the hole 18 15 presented over an unbored surface of the tie 1 in which a spike may take a firm hold in the new wood. The advance of the base-plate brings the holes 20, 21, 22 and 23 into register with the vacated spike holes in 20 tie 2 ready for the insertion of the spikes, and the holes in tie 3 left vacant by the withdrawal of spikes from the holes 20, 21 and 23, receive the newly inserted spikes corresponding to 13, 14 and 15 in the same 25 or another tie-plate introduced beneath the rail on tie 3.

Ties as now treated with preservatives resist the action of the elements and ordinary wear of service for long periods if not 30 otherwise damaged; by the use of this invention the crushing strains at the rail-joints are distributed by the base-plate over wide surface areas on two adjacent ties, thus reducing the effect of usual unavoidable 35 wear, and the mechanical damage due to a multiplicity of spike-holes is eliminated and the tearing out of the spikes as in a fixed joint is entirely avoided.

To stiffen the joint and reduce the shocks 40 to the ties due to the depression of one rail-end relatively to the other at the passage of a car wheel, the rail-bars 25, formed as shown, are employed. Each has a heavy ridge or flange 26 on the inner face at each 45 margin, with the upper and lower edges inclined or beveled to match to the under face of the rail-head and upper face of the rail-base, and are applied in pairs clamped to the rail by track-bolts 27 extending through 50 the bars and web of the rail and held by washers 28 and nuts 29. The cross-section of the bars is such as to insure great strength and stiffness and as both edges are practically alike, with the holes for the 55 track-bolts located at the midheight, they may be applied with either edge uppermost.

The impact of the under surface of the rail-heads upon the upper edges of the rail-bars at and immediately adjacent to the 60 rail joint 6, eventually produces a slight notch or depression in such edges, lessening the effective support of the rail-ends at this point. When this depression has increased sufficiently to require attention, it is only 65 necessary to remove the bars and reverse

them by turning the unimpaired lower edge uppermost beneath the rail-head with the damaged edge in contact with the rail-base, in which latter contact the depression is of no consequence, and the bar is thus conditioned for another long period of service. 70

By thus reliably joining and supporting the rail-ends at the joint, the shocks delivered by the rail-ends to the base-plate 4 and transferred to the ties are greatly 75 lessened.

Modifications may be made in the forms and proportions of the parts in adapting the invention to various conditions of service and to the standards of construction adopted 80 by various railways.

Cut-spikes or screw-spikes may be employed as dictated by conditions or preference, or on bridge structures and the like, bolts may be substituted. 85

In the usual method in which the rail joints are fixedly secured to the ties, the creep due to travel in one direction, expansion, or other causes, carries the fastened ends of the ties with the rail, resulting in 90 skewing these ties into angular positions, requiring correction and the respacing of the adjacent ties. By the use of the present invention this fault and the labor and expense attending such correction are avoided. 95 The same applies to re-laying rails differing in length from the removed rails and having the rail-joints differently located relatively to the ties.

I claim:—

1. In a rail-joint, a base-plate adapted to lie upon two adjacent ties and to support the abutting rail-ends with freedom for the rail to move longitudinally thereon, means for joining said rail-ends, spike-holes 105 in said base-plate located to match the spike holes in a tie-plate, and means received in such spike holes for holding said base-plate and tie-plate to the ties.

2. In a rail-joint, a base-plate adapted to 110 lie upon two adjacent ties and bridge the space between them and support the abutting rail-ends with freedom of the rail to move longitudinally thereon, a tie-plate on the succeeding advanced tie, means for fastening said base-plate and tie-plate to such ties, said base-plate having spike-holes 115 matching the spike-holes in said tie-plate, substantially as and for the purposes herein set forth.

3. In a rail-joint, a base-plate adapted to lie upon two adjacent ties and bridge the space between them and to support the abutting rail-ends, longitudinally extended ribs on said base-plate adapted to receive 125 the rail-base of said rail-ends between them and permit said rail-ends to move freely longitudinally and to hold said rail-ends against lateral movement, a tie-plate on the succeeding advanced tie, means for join- 130

ing said rail-ends, removable fastening means for securing said base-plate and tie-plate to such ties, said base-plate, having spike-holes at the front and rear ends, located to match the spike-holes in said tie-plate, substantially as and for the purposes herein set forth.

4. A base-plate for a rail-joint, adapted to lie upon two adjacent ties and bridge the space between them, longitudinally extending ribs on said plate, spike-holes through said plate exterior to said ribs, located to match spike-holes in a tie-plate, and spike-holes extending through said ribs and plate.

5. A base-plate for a rail-joint, adapted to lie upon two adjacent ties and bridge the space between them, longitudinally extending ribs on said plate, grooves in the latter exterior to said ribs, and spike-holes ex-

tending through said plate in said ribs and grooves.

6. The method of conserving railroad ties at a rail-joint, consisting of supporting the rail-ends on a base-plate with freedom to move longitudinally thereon, such base-plate bridging the space between two adjacent ties, and having spike-holes for the reception of removable fastening means extending through such holes into said ties, such spike-holes arranged to match the holes in the next advanced tie produced by the removable fastening means for a rail-supporting tie-plate on such advanced tie, when said base-plate is shifted forward, and the holes in the rearward tie thus vacated matching the holes in such tie-plate.

In testimony that I claim the invention above set forth I affix my signature,

ANDREW J. NEAFIE.
